UNITED STATES PATENT OFFICE.

WILLIAM H. STEDMAN, OF MANSFIELD, CONNECTICUT, ASSIGNOR TO THE MERROW MACHINE COMPANY, OF HARTFORD, CONNECTICUT, A CORPORATION OF CONNECTICUT.

SEWING MACHINE.

1,418,682.

Specification of Letters Patent. Patented June 6, 1922.

Application filed May 17, 1919. Serial No. 297,853.

To all whom it may concern:

Be it known that I, WILLIAM H. STEDMAN, a citizen of the United States, residing in the town of Mansfield, county of Tolland, 5 State of Connecticut, have invented certain new and useful Improvements in Sewing Machines; and I do declare the following to be a full, clear, and exact description of the same, reference being had to the accompanying drawings, forming a part of this specification, and to the characters of reference marked thereon.

This invention relates to sewing machines, and especially embraces various improvements applicable, as illustrated in the drawings, to a trimming and overseaming machine of the well known Merrow high speed type, distinguishing characteristics of which have heretofore been described at length as 20 in United States Patent #733,760, dated July 14th, 1903.

In such a machine, supporting, feeding and trimming elements engage the work in close proximity to each other, and to the 25 needle and a cooperating looper or loopers. The needle, loopers, cutter blades, and feeding elements, are all preferably associated with suitable carriers in a manner to permit of their adjustment and replacement. Accessibility of the means employed for thus 30 associating with their respective carriers the elements mentioned, is for obvious reasons, of prime importance, and to fulfill this desideratum the present invention consists in 35 a novel arrangement of mechanism including a presser-foot which is movable from its normal position to one of non-interference with manipulation involved in the setting of various parts and also threading of the 40 needle.

The invention further consists in the provision for elements of the trimming mechanism and presser-foot of a common support in combination with a convenient and efficient 45 arrangement of separate devices for respectively controlling the trimming mechanism and presser-foot.

Other new features incidental to the development of structural combinations for 50 effecting the advantages mentioned are included in the present invention which, in connection with the accompanying drawings forming a part of this specification, will now be described in detail.

In the drawings,

Figure 1 is a plan view of a trimming and overseaming machine embodying my invention, the presser-foot being illustrated as moved away from its normal position. Fig. 2 is a front elevation of the machine. Fig. 3 is an end elevation as viewed from the left in Fig. 2. Fig. 4 is a rear elevation. Fig. 5 is a plan view partly in section showing the support for the presser-foot, upper cutter carrier, and other associated parts. Fig. 6 is a detail view of a shaft engaging sleeve. Fig. 7 is a detail view of a modification of the sleeve shown in Fig. 6. Fig. 8 is a view of the mechanism shown in Fig. 5, as seen from the right. Figs. 9 and 10 are views showing the presser-foot support in section and other details of the presser-foot mechanism partly in section and partly in elevation,—and Fig. 11 is a detail view in section showing the pivotal relation between the presser-foot and its shank.

Similar characters of reference designate similar parts throughout the several views.

Referring to the drawings, the general characteristics of one type of machine in which my invention may be conveniently embodied may be briefly described as follows:—The overedge stitch forming implements shown, comprise the curved eye-pointed needle 3, lower looper 4, and upper looper 5. The needle is secured in a carrier 6, pivotally mounted on a stud 7, about which the carrier is oscillated through the medium of a link 8, which connects said carrier with an eccentric stud 9, projecting from the head 10, of a shaft 11, which is supported by the machine frame 12. The curved path followed by the needle extends above and below a needle plate 13. The lower looper and upper looper cooperate with the needle respectively on opposite sides of the needle plate, and with each other below the plane of the needle plate, to form overedge stitches in a manner well known to those familiar with the sewing art, suitable movements of these implements being imparted by well known mechanism enclosed within the machine frame. Illustration of this enclosed mechanism has been omitted from the drawings as unnecessary to an understanding of the present invention, the driving shaft of the machine, however, is shown projecting beyond the ma-

chine frame at 14, where it is provided with a combined handwheel and driving pulley 15.

The needle plate 13, is secured to a standard 17, which also serves to support the forward end of a work plate 18, which is further supported by a bracket 19, toward the rear of the machine, a pivotal connection 20, being provided between said bracket 10 and work plate whereby the latter may be swung away from the needle plate and adjacent parts to render them more accessible for inspection and adjustment. Below the needle plate the standard 17, affords a convenient support for the holder of a cutter, involving construction hereinafter more fully described in connection with a trimming mechanism.

Feed mechanism in so far as it pertains 20 to improvements herein to be set forth, includes a presser-foot 22, and feed dogs 23. Regarding the latter it will be sufficient for the present disclosure to state simply, that to them, suitable fabric advancing movements may be imparted by mechanism indicated in a general way by 24. The presser-foot 22, in performing its function of holding the fabric to be stitched in contact with the feed dogs, partakes from them and from 30 means to be described for effecting a yielding opposing pressure, a slight movement which is preferably substantially at right angles to the plane of the work engaging surface of the needle plate. To provide for 35 such a movement of the presser-foot, that is, one that deviates but slightly from the vertical with respect to the needle plate, I employ a presser-foot carrier, indicated in a general way by 26, comprising an oscillatory member 27, and a presser-foot shank 28. The oscillatory member is associated with a shaft 29, journaled in bearings of a support 30, secured to the rear side of the machine frame. The axis of this shaft extends 40 in a plane substantially coincident with the plane of the work engaging surface of the needle plate, and inasmuch as the shaft is quite remote from the presser-foot, the slight arc of movement of the latter 45 about the shaft axis will deviate but little from a tangent thereto which is vertical to the needle plate, and it follows that the presser-foot movement is to all practical purposes a rectilinear one which is desirable. However, the presser-foot is also pivoted or hinged to its shank as indicated particularly in Fig. 11, so that in addition to 50 its bodily movement about the center of movement of its oscillatory carrier, it is free 55 to move angularly upon the stud 28', laterally extended from the presser-foot shank, which permits it to accommodate itself to variations in thickness of the fabric comprising the work.

60 It will be observed that the oscillatory

member 27, of the presser-foot carrier, as shown in the drawings, is made up of two parts 32 and 33, this being desirable, although not essential, for convenience in manufacture. The part 32, is of yoke form 70 and adapted to straddle the separated bearings 34 and 35, of the support 30. Thus while the shaft 29, extending through these bearings, supports the yoke 32, it is free to rock and move endwise therein for a purpose that will hereinafter appear. The part 33, of the presser-foot carrier is secured as by a screw 36, to an offset termination 37, of an arm 38, upwardly extending from one end of the yoke 32, said termination having a tongue 39, mating a groove 40, in the part 33, to secure alignment of the connected parts. By virtue of this arrangement, the part 33, extends above and in the direction of the line of stitching, and when 85 the presser-foot shank is aligned therewith, the presser-foot is positioned either in normal working relation to the feed dogs and needle plate, or in such lifted relation thereto as permits introduction or adjustment of 90 work thereunder. With the presser-foot in this position, the needle and other implements adjacent the needle plate are somewhat obscured, as is common in sewing machines, and, to render them more conveniently accessible and exposed to view, provision is made whereby the presser-foot may be readily swung away from the needle plate, (see Fig. 1) and with equal facility returned and locked in normal relation. To 100 permit of such movement, a simple expedient may involve a pivoted relation of the presser-foot shank 28, and oscillatory member 27. The part 33, of the last mentioned member is channeled at 41, to receive the shank 28, and also, said part 33, is provided with an opening 42, to receive a head 43, at the end of the shank, the head 43, being pivoted on the stud or pin 44, which is supported by ears or lugs 45, projecting from part 33, coextensively with the width of head 43. At its forward end the head 43, is slotted at 46, to receive the head 47, of a latch 48, which is pivoted at 49, between flanges 50, which project from one side of shank 28. A spring 51, housed within a bore 52, in the head 43, bears against the head of latch 48, and causes it, when the shank and part 33, are in aligned relation, to engage a shoulder 54, of the part 33, formed at the forward edge of opening 42, thereby to securely hold the parts in said aligned relation. In this position, the tail 55, of latch 48, extends beyond the flanges 50, so that it may be conveniently depressed by an operator to disengage the latch, whereupon the shank 28, may be swung upon its pivot to move the presser-foot bodily away from the stitching and trimming area. While in this position the 130

presser-foot may still function to hold the work during rethreading of the stitching implements or inspection or adjustment of mechanism in the vicinity of the stitching point. To reestablish the normal relation of the presser-foot, it is simply swung into position over the needle plate, the latch automatically springing into locking relation.

As previously intimated, means including a spring are employed for moving the presser-foot toward the needle plate with a yieldingly effective pressure. This may be advantageously applied at the forward end of part or arm 33, above which a suitable support may be extended without obstruction to convenient operation of the machine. Such a support is provided in the bracket 60, secured to the end of the machine frame. A head 61, on this bracket, is bored at 62, to receive the plunger 63, which has a slotted end 64, to engage a rounded surface 65, on arm 33. The slotted form of the end of the plunger keeps it from turning and maintains its pressure transmitting surface in proper relation to the surface 65. Furthermore the side walls of the slot afford supplemental support to resist lateral displacement of arm 33, due to pressure to which it might be subjected to from hasty swinging of the presser-foot to and from its normal relation. A reduced shank 66, of plunger 63, is surrounded at its upper end by a guiding sleeve in the form of a screw 67, which is threaded into bore 62. A spring 68, surrounds the plunger shank, bearing at one end against the shoulder 69, of the plunger and at the other end against screw 67. By adjusting said screw, pressure of spring 68 against the plunger may be obtained in any desired degree, and such adjustment may be held against unintentional alteration by the jamb nut 70. I desire here to direct attention to the fact that the axis of movement of the plunger 63, is substantially at right angles to a radius extending from the axis of oscillation of the presser-foot carrier to the engaging surfaces of the plunger and said carrier. An advantage exists in this relation, in that the slight arc of movement of the surface of the carrier engaged by the plunger is substantially tangent to the axis of movement of the plunger so that slippage between the engaging elements is inconsequential with respect to producing undesirable friction or wearing of the surfaces.

Means for lifting the presser-foot for the purpose of adjusting or introducing the work thereunder, include a lever 75, pivotally mounted at 76, between lugs 77, of the previously mentioned support 30. A cam surface 79, on lever 75 is adapted to engage a roll 80, mounted on the pin 81, between lugs 82, of the yoke 32. To lift the presser-foot, lever 75, is moved conveniently by

hand, or by knee or foot operated mechanism, (not shown) to engage its cam surface with roll 80, thereby swinging the presser-foot carrier about its axis against the pressure of spring 68, and moving the 70 presser-foot away from its normal proximity to the needle plate. To prevent undue raising of the presser-foot, a stop screw 84, is threaded into support 30, to engage yoke 32, below roll 80. A suitable adjustment of 75 the screw may be secured against displacement by jamb nut 85. When lever 75 is released to permit lowering of the presser-foot under influence of spring 68, it is moved to the position shown in Fig. 9, by a plunger 80 88, actuated by the spring 89, the plunger being guided by a bore 90, in the machine frame. The thrust of the spring 89, is resisted by contact with the machine frame and is exerted against the plunger head 91, 85 which enters a retaining recess 92, in lever 75, the latter being normally held by action of the spring so that an adjustable stop 93, carried by the lever engages a cooperating stop element as the pin 94. In this position of the lever its cam portion is clear of roll 80, and the presser-foot together with associated parts is free to function properly in the normal action of the feeding mechanism.

Reference is now again made to the bracket 60, for the purpose of describing the association therewith of certain thread guides, comprising elements of take-up mechanism which includes the take-up arm 100, secured 100 to and movable with the needle carrier actuating link 8. This arm 100, at its outer end is extended into the plane of movement of the needle, and provided with a thread receiving eye 101. Directly above the path 105 traversed by the thread engaging portion of the take-up arm, a thread guiding tube 102, is mounted in bracket 60, and below said path a thread guide 103, extends from the free end of arm 104, said arm being secured 110 in a guideway 105, of bracket 60, by a screw 106, passed through an elongated slot 107, whereby means is provided for adjustment of the thread guide to regulate the take-up action. Due to this arrangement which permits of thread eye 101, of the take-up arm, thread guide 102, and thread guide 103, being substantially aligned, (see Fig. 9) threading of the machine is considerably 115 facilitated, in that a threading wire may be 120 simultaneously passed through the three take-up elements.

Trimming mechanism particularly well adapted in the type of machine shown for association with such mechanism as has 125 already been described, includes the normally stationary cutter 110, and the movable cutter 111, which for convenience will herein-after be referred to respectively as the lower cutter and the upper cutter, the former being 130

positioned beneath the work and the latter operable from above the work which is introduced horizontally into the machine. The lower cutter is clamped in a slide 112, suspended in the standard 17, below the needle plate. A spring 113, housed within the slide, bears at one end against an abutment plate 114, and exerts its thrust against the slide, tending constantly to move it toward the right as seen in Fig. 5, so that the lower cutter, for a purpose that will presently appear is yieldingly pressed against the upper cutter, the latter being operable in a cutting plane extending transversely to the plane of the work. The upper cutter is held in a carrier 116, secured to shaft 29, between the aforementioned bearings 34 and 35. These bearings are connected by a web 117, which forms a housing for the hub of carrier 116. Opposite this housing the machine frame is provided with an opening 118, to clear the carrier adjacent the hub thereof, the means of securing the carrier to the shaft 29, being shown as a set screw 119, threaded into the carrier hub. This set screw is made accessible from the rear of the machine by providing the openings 120 and 121, respectively in web 117, and the yoke 32. Oscillatory motion is imparted to the upper cutter carrier by an eccentric 122, fixed to the shaft 11, said eccentric being surrounded by the rectangular block 124, engaged by the yoke 125, of said carrier. It is desirable that the trimming cutters be shiftable laterally to vary the line of trimming with respect to the line of sewing. The arrangement herein provided for effecting an adjustment of this character involves shifting of the upper cutter carrier shaft 29, in the direction of its longitudinal axis. The upper cutter carrier being fixed to the shaft moves with it, and its endwise adjustment locates the upper cutter accordingly, with respect to the line of stitching while the lower cutter by virtue of its spring controlled movement toward the upper cutter, automatically adjusts itself to any cutting plane in which the latter may be located. Means for adjusting shaft 29 in the direction of its length, will now be described.

In alignment with bearings 34 and 35, a third bearing 130, is provided on support 30, to receive the sleeve 131. Near one end, there is formed in this sleeve an inclined slot 132, to receive the end of a screw 133, threaded into the support 30. At its other end a slightly reduced part of the sleeve extends beyond the bearing and has keyed thereto an actuating lever 134, by means of which the sleeve may be rocked about its longitudinal axis, and when it is so rocked the sleeve moves in the direction of said axis by virtue of engagement of the fixed pin or screw 133 with the inclined slot 132. The shaft 29, is associated with the sleeve 131

in such a manner that it is longitudinally immovable relatively to the sleeve but free to turn therein, therefore when the sleeve is rocked the shaft is moved endwise and the trimming cutters are adjusted accordingly. The relation set forth between the shaft and the sleeve is secured by providing a head 135, on the shaft to engage a shoulder 136, formed by counterbore 137, into which is threaded the screw 138. By adjusting the screw the head of the shaft may be confined between the end of the screw and the shoulder with just sufficient clearance to permit the shaft to turn freely. The screw 138 when thus suitably adjusted may be held against displacement by the jamb nut 139. This nut may also serve to retain the lever 134, against endwise movement along the sleeve.

The construction involved in the described association of shaft 29 and sleeve 131, simplifies assemblage of the parts and provides for convenient adjustment to take up wear which would permit lost motion in the action of the cutter shifting mechanism. Furthermore the arrangement permits of substitution for sleeve 131, of sleeve 140, such as shown in Fig. 7, the idea being to provide two simple interchangeable parts capable of association with the trimming mechanism to render it either adjustable or non-adjustable with respect to the width of trimming effected thereby. For a class of work which requires no variation in the width of trimming, a machine may preferably be employed equiped with the non-movable sleeve 140. In order to hold a sleeve of this type fixed in place, it is simply provided with a hole 141, to receive and fit the end of screw 133. No lever is necessary at the outer end of this sleeve which is instead provided with a knurled head 142. In other respects the sleeve 139 is the same as sleeve 131.

In connection with trimming mechanism arranged for adjustment of the cutters to vary the width of trimming it is convenient to have stop means by which to repeatedly establish various adjustments. The range of movement of the actuating lever 134 in establishing such adjustment of the trimming cutters is of sufficient extent to render the hub of this lever a suitable support for certain stop elements as the pins 143 and 144, which are adapted to engage a fixed stop element 145, secured to support 30 by a screw 146. The pins 143 and 144 are fixed in the lever hub to respectively engage stop 145 when the trimming cutters are at the opposite extremes of their adjustment. Intermediate adjustments of the cutters may be determined by the position of a movable stop pin 147, which may be inserted in any one of the holes 148. When stop pin 147 is not in one of the holes where it functions

as a stop, it may be kept conveniently at hand by inserting it in hole 149.

In Fig. 8, lever 134 is shown in position to engage stop 144 with stop 145, such relation serving through described parts to place the cutters at the limit of their adjustment toward the line of stitching. In order to hold the cutters in this position against an opposing pressure of the spring associated with the lower cutter carrier, the lever 134 is provided with the spring actuated detent 150, operable against the stop shoulder 151, on the support 30. This arrangement insures ease and smoothness of operation in the actuating lever 134, as well as to prevent too free an action thereof when in intermediate positions.

While I have specifically shown and described one convenient form of embodiment of my invention it is to be understood that various changes as to form, construction and arrangement of parts, may be made without departure from the spirit of the invention as defined by the following claims.

Having thus described my invention, what I claim is,—

1. In a sewing machine, a presser-foot supporting and operating mechanism comprising a carrier pivotally mounted on a horizontal axis to oscillate in a vertical plane for effecting engagement and disengagement of the presser-foot with the work and to hold the work in engagement with the feeding dog, a forwardly projecting presser-foot shank connected with said carrier by a hinge connection having its axis substantially at right angles to the axis about which the carrier oscillates, and releasable means for locking said shank against pivotal movement on its hinge connection.

2. In a sewing machine, a work plate, a presser-foot, a carrier for the presser-foot mounted to permit the presser-foot to move toward and from the work plate about an axis extending substantially in parallelism to the work engaging surface of the work plate, and a pivotal connection between normally aligned members of the carrier having its axis substantially at right angles to the work engaging surface of the work plate.

3. In a sewing machine, a work plate, a presser-foot, a carrier mounted to move toward and from the work plate about an axis extending substantially in parallelism to the work engaging surface of the work plate, a presser-foot shank pivotally connected to the carrier about an axis extending substantially at right angles to the work engaging surface of the work plate, and a releasable means for locking the shank against movement on its pivotal connection.

4. In a sewing machine, a work plate, a presser-foot, a support, a carrier extending above and in substantial parallelism with the line of stitching, one end of the carrier

being offset and depended for pivotal association with the support about an axis extending substantially in the plane of the work engaging surface of the work plate, and a shank for the presser-foot normally aligned with the arm and pivoted thereto about an axis extending substantially at right angles to the work engaging surface of the work plate.

5. Presser-foot mechanism including in combination, a presser-foot, an arm adapted at one end for pivotal support and having a channel extended for a part of its length from the opposite end, a shank associated with the presser-foot, pivoted to the arm and adapted to be supported by walls of the channel, and supplemental supporting means cooperating with the arm adjacent to its channeled portion.

6. In a sewing machine, in combination with feed mechanism including a work plate and a presser-foot, a support, an oscillatory member pivoted at one end to the support and having an arm substantially parallel with and extending above the line of stitching, supplemental supporting means cooperating with the arm remote from its axis of movement, and a shank for the presser-foot pivotally associated with said arm intermediate its axis of movement and its supplemental supporting means.

7. In a sewing machine, a work plate, a presser-foot, a support, a presser-foot carrier extending above and in substantial parallelism with the line of stitching, one end of the carrier being offset and depended for pivotal association with the support about an axis extending substantially in the plane of the work engaging surface of the work plate, and means for applying a yielding pressure to the carrier to move the presser-foot toward the work plate, said means including a contact element affording lateral support for the carrier and engaging the latter substantially at a point which upon movement of the carrier describes an arc to which the line of movement of the contact element is tangent.

8. In a sewing machine, a work plate, a presser-foot, supporting and operating mechanism including a carrier pivotally mounted for movement to effect cooperation of the presser-foot with the work plate to hold the work, a presser-foot shank connected with the carrier by a pivotal connection having its axis substantially at right angles to the work engaging surface of the work plate, a plunger slotted to engage the carrier and supported in close proximity thereto, and a spring for yieldingly actuating the plunger to move the presser-foot toward the work plate.

9. In a sewing machine, in combination, a work plate, a presser-foot, a support, a carrier extending above and in substantial

parallelism with the line of stitching, one end of the carrier being offset and depended for pivotal association with the support about an axis extending substantially in the 5 plane of the work engaging surface of the work plate, and a shank for the presser-foot normally aligned with the arm and pivoted thereto about an axis whereby the presser-foot may be swung bodily away from its 10 normal position to another position where it may function to hold the work while giving access to mechanism in the vicinity of the stitching point.

10. In a sewing machine, in combination, 15 a work plate, a support, an oscillatory member associated with the support for movement about an axis extending substantially in the plane of the work engaging surface of the work plate, a presser-foot shank pivotally associated with the oscillatory member for movement about an axis whereby it may be swung from its normal position without changing its normal inclination to said plane of the work plate, and a presser-foot 20 pivotally associated with the shank for movement about an axis extending in parallelism to the axis of the oscillatory member.

11. Presser-foot mechanism including in combination, a presser foot, an arm adapted 30 one end for pivotal support and having a channel at its opposite end, a shank for the presser-foot fitted to the channel in the arm, a pivotal connection between the shank and the arm, and a spring actuated latch lever 35 pivotally associated with the shank and operable through movement of the shank to automatically engage a shoulder on the arm to positively lock the shank and arm in normal relation.

40. 12. Presser-foot mechanism including in combination, a presser-foot, an arm adapted at one end for pivotal support and having a channel at its opposite end, a shank for the presser-foot fitted to the channel in the arm, 45 a pivotal connection between the shank and the arm, a latch lever pivotally associated with the shank, one end of the lever being engageable with a shoulder upon the arm to lock the shank in normal relation to the arm, 50 the other end of the lever being depressible to release the locking engagement, and a spring for actuating the latch.

13. Presser-foot mechanism including in combination, a presser-foot, an arm adapted 55 at one end for pivotal support, and having a channel at its opposite end, a shank for the presser-foot fitted to the channel in the arm and terminating in a head formed to occupy a recess laterally extended from the channel, 60 a pivotal connection between the head and the arm, a latch lever pivotally held in a slot in the shank, one end of the lever being engageable with a shoulder formed by the recess to lock the shank in normal relation 65 to the arm, the other end of the lever being

depressible to release the locking engagement, and a spring housed within the head of the shank for actuating the latch.

14. In a sewing machine, in combination with feed mechanism including a needle plate and a presser-foot, a support, an oscillatory member pivoted at one end of the support and having an arm substantially parallel with and extending above the line of stitching, a shank for the presser-foot pivotally associated with said arm to permit bodily movement of the presser-foot about an axis extending transversely to the work engaging surface of the needle plate, means for laterally supporting the arm remote 70 from its axis of movement, and means for yieldingly actuating the oscillatory member 75 to move the presser-foot toward the needle plate.

15. In a sewing machine, in combination with feed mechanism including a needle plate and a presser-foot, a support, an oscillatory member pivoted at one end to the support and having an arm substantially parallel with and extending above the line of stitching, a shank for the presser-foot pivotally associated with said arm to permit 80 bodily movement of the presser-foot about an axis extending transversely to the work engaging surface of the needle plate, a 85 plunger slotted to engage the arm and supported in close proximity thereto, and means for yieldingly actuating the plunger to move the presser-foot toward the needle plate.

16. In a sewing machine, in combination with feed mechanism including a needle plate and a presser-foot, a support, an oscillatory member pivoted at one end to the support and having an arm substantially parallel with and extending above the line 100 of stitching, a plunger slotted to engage the arm and supported in close proximity thereto, a shank for the presser-foot pivotally associated with and supported by said arm intermediate its axis of movement and the 105 part engaged by the plunger, and means for yieldingly actuating the plunger to move the presser-foot toward the needle plate.

17. The combination with stitching mechanism including a needle carrier and actuating elements therefor operably supported on one side of the line of stitching, of a presser-foot, a needle or work plate, a carrier for the presser-foot pivotally supported on the needle carrier side of the line of stitching and including an arm extending in the direction of the line of stitching on the opposite side thereof from the needle carrier, a bracket extending above the line of stitching, means supported by the bracket for 115 applying a yielding pressure against the arm to move the presser-foot toward the needle or work plate, thread guides supported by the bracket, and a take-up element 120 supported by the bracket, and a take-up element associated with the needle carrier actuating 125 130

mechanism and movable into alignment with the thread guides.

18. The combination with stitching mechanism including a needle carrier and actuating elements therefor operably supported on one side of the line of stitching, of a presser-foot, a needle or work plate, a carrier for the presser-foot pivotally supported on the needle carrier side of the line of stitching 5 and including an arm extending in the direction of the line of stitching on the opposite side thereof from the needle carrier, a bracket extending above the line of stitching, means supported by the bracket for applying a yielding pressure against the arm to move the presser-foot toward the

needle or work plate, thread guides supported by the bracket, a take-up element associated with the needle carrier actuating mechanism and movable into alignment 20 with the thread guides, and a shank for the presser-foot pivoted to the arm whereby the presser-foot may be moved from its normal position to facilitate threading of the thread guides, take-up element and needle. 25

In testimony whereof I have signed my name to this specification in the presence of two witnesses.

WILLIAM H. STEDMAN.
